F. H. REXTREW,
EYE PROTECTOR,
APPLICATION FILED JAN. 23, 1915.

1,186,943.

Patented June 13, 1916.

UNITED STATES PATENT OFFICE.

FRANK HOWARD REXTREW, OF HAMMOND, INDIANA, ASSIGNOR TO ROY E. GREEN, OF WHITING, INDIANA.

EYE-PROTECTOR.

1,186,943.

Specification of Letters Patent. Patented June 13, 1916.

Application filed January 23, 1915. Serial No. 4,040.

To all whom it may concern:

Be it known that I, FRANK HOWARD REXTREW, a citizen of the United States, residing in the city of Hammond, county of Lake, 5 and State of Indiana, have invented certain new and useful Improvements in Eye-Protectors, of which the following is a specification.

My invention relates to eye shields or 10 protectors adapted to be worn upon the face to protect the eyes, as from sunlight, wind and dust.

In one aspect of the present invention, its 15 object is to improve the construction set forth in my Letters Patent of January 5, 1915, No. 1,123,376, with a view to providing a lighter device, one having end walls free from an outstanding fold somewhat 20 objectionable from the standpoint of finish and under which dust may find its way and prove objectionable, one in which there is only a single piece in the upper portion of the device in its more simple form as distinguished from two layers of the material 25 and between which two pieces dust and dirt may accumulate, and one also in which the visual and shading properties of the upper portion of the device are improved in various combinations of colors and arrangement. 30 In other respects its objects are to provide improved means for ventilating the device, both for comfort and to prevent fogging of the device under certain conditions.

General objects are to provide an eye 35 shield or protector which is light, strong and durable, of simple construction, and comfortable and effective in use.

Other objects and advantages will appear hereinafter.

40 In the accompanying drawings which form a part of this specification, Figure 1 shows a rear view of a preferred form of upper and lower sections secured together preparatory to turning in the ends; Fig. 2 shows the upper portion of Fig. 1 without the ventilating provisions; Fig. 3 shows a modified form of the lower portion of Fig. 1; Fig. 4 shows the device as in use, the scale being reduced; Fig. 5 shows the device 45 of Fig. 4 in side view; Fig. 6 is a sectional view of the device as on the line 6—6 of Fig. 4 during the process of construction, the scale being enlarged; Fig. 7 is an end view of the shield proper complete; and Fig. 8 is

a perspective view of a fragment of the rubber binding. 55

The shield or protector proper is formed preferably of thin and flexible material such as what is known as artificial ivory, celluloid, pyrolin, etc. The upper portion 10 60 preferably comprises a relatively long strip of the material mentioned of sufficient width to provide desired shade properties, and preferably of the proportions shown with respect to the lower part or parts, the outer 65 ends being rounded to provide a rounded edge at the end walls of the completed device. The lower part of this element 10 is preferably cut so as to provide a clearance, as at 11, to increase the scope of the vision 70 when the parts are made in the relative proportions shown, and a central preferably pointed portion 12 is provided, hereinafter referred to.

The lower portion 13, Fig. 1, or 13^a, Fig. 75 3, is preferably somewhat shorter than the upper portion and preferably has provisions for accommodating the nose of the wearer, as the notch 14. The ends of the element 13 are preferably cut off on an angle, as illustrated, to provide clearance for the folding operation, which cutting may be of greater or less angularity or may even be dispensed with in modifications of the preferred form. I also prefer to provide the tips or projections 15 integral with the portion 13, and substantially on the angle shown, as when the edge 16 thereof is brought to the edge 17 in the folding operation the end portions are in suitable position for being secured together, such cutting thus providing a guide for the folding operation. The provision of the tips 15 also strengthens the device at its apices or corners 18. The projections 15 may be omitted, however, as at 19, 95 Fig. 3. The lower portion of the device thus comprises substantially two wings A and B which are before the eyes of the wearer when the device is normally in use. Preferably I make the lower portion 13 in one piece, as 100 shown in Fig. 1, but the wings A and B may be in two pieces, as in Fig. 3 for instance, in which general form they may be made separately according to the size of the material available for use or as may prove advantageous in modified forms of the invention. 105

The portions A and B are secured to the upper portion along contiguous edge por-

tions thereof longitudinal or substantially longitudinal of the device and between its sides. To this end I preferably overlap the upper and lower portions slightly, and, 5 by the use of preferably transparent cement, the parts are caused to adhere together. A joint is thus formed between the upper and lower portions, which joint is the boundary between the clear lower portion 10 through which the wearer may see freely and substantially unobstructedly and the upper or shade portion through which, in the preferred construction, the wearer can see also, but not so well owing to the darker 15 color of such upper portion. But whether such upper portion have some visual properties or be opaque, the joint or line of connection between the portions shows the wearer what degree of tilting of the head 20 is necessary to get the advantages of clear vision, partially restricted vision or partial or complete shading, and in practice this line or joint is maintained above or below the pupillary range as a particular 25 situation or occasion may render necessary or suggest. The cement preferably is applied throughout the overlapped portions as at 10^a, Fig. 1.

The upper portion 10 is preferably of 30 relatively dark material, or such as has light-obstructing properties, when the device is formed as a combined eye shade and protector, which is the preferred construction and use. The lower portion 13, 13^a, or 35 the equivalent, is of substantially clear material, or it may be described as transparent or substantially transparent, which is intended to denote broadly the property of permitting objects to be viewed clearly 40 therethrough. Material of the character specified is made with various tints or colors, such as amber and green, black, orange, etc. and is also untinted. In my 45 constructions I use various combinations of colors or shades. For instance, a substantially opaque or dead white, dead black, darker green, deep orange, etc., for the upper portion 10, while for the lower portion or portions I employ either untinted 50 material or the lighter shades of amber, orange, etc., the upper portion always being relatively darker or having greater light obstructing properties than the lower portion in the preferred form, in order to shade 55 the eyes.

The upper and lower elements having 60 been secured together in any approved way, preferably by cementing, the end portions of these elements may be folded or turned 65 inward, and, in the form illustrated, until they come into overlapped relation. A coating of cement having been applied to one end portion, as at 10^b, the edge 20 of the element 10 is drawn over the edge 17 of the element 13 until the edge 20 is substantially

in the position shown in Fig. 4, when, by the application of holding means, for instance the spring clip C, Fig. 6, the parts are held in their overlapped relation until the cement has set. A wall is thus provided 70 at each end of the device, which wall is of continuous formation on the outside, free from folds or other obstructions, is exceedingly neat, and as the edge 20 is firmly cemented to the lower portion 13 the device 75 as a whole presents an unusually smooth and clean-cut effect, and is free from folds or overlaps likely to accumulate dust and dirt. The construction also provides notable security to the device when one end 80 is folded inward and the other end brought around and folded over it, thus bringing the device into small compass for carrying in the pocket. The relatively narrow lap joint connecting the upper and lower sections of 85 the protector effectually prevents any breaking or splitting at the corners or angles 18 formed by the front wall and the end walls, especially when the tips 15 before mentioned are provided. With protectors heretofore proposed, in which a single piece of celluloid was notched at the end edges and the notched edges then cemented together to form the end walls of the protector, splitting at the corners was a serious and unavoidable defect. An eyelet, as 90 27, may be employed to hold overlapped end portions or for securing the holding means, as 21, if desired. The protector formed as thus far described may be provided with means for securing the same 95 upon the face, as for instance the flexible and elastic ear loops 21, and thus be worn. I prefer, however, to provide accessories to the simple form of device thus built up, for 100 instance the rubber binding 22, preferably circular in cross area and split longitudinally and toward the center in one wall, the edges of the device being inserted in the split of the rubber and there secured, 105 as by cement.

Another important feature of the device is in my improved means for ventilating the same. I may provide the usual holes 23 for ventilation; but the present improvement 110 is in a plurality of openings, as 24, in the upper portion 10, and, beyond these openings as viewed from the front, a deflecting element, suitably a strip of material as 25, preferably of the same material and color 115 as is the element 10, which may be cemented or otherwise secured directly upon the back of the element 10 and caused to stand away slightly from the openings, as 24, on the inside of the device, so as to deflect, preferably downward, the air entering the openings 24. I preferably make the strip 25, or the equivalent, of such proportions that air 120 will be deflected over substantially the entire front wall of the device, although one 125 130

relatively short deflector over each eye would give improved results over the older methods. This ventilating provision is important not only from the standpoint of comfort, but in preventing the "fogging" of the shield due to the otherwise warm moisture of exhalation from the face contacting the colder surface of the shield.

A further important provision is in means for shading both eyes from light coming from the side of the wearer, as well as in equally limiting the field of vision of both eyes in the direction of the sides. This has reference to the portion 12, preferably in the form of a sharply pointed projection and substantially as illustrated, the preferred form, shape and location of this element or provision having resulted from many experiments and modifications leading to the present result. Looking at Fig. 4 it will be apparent that light coming slantingly toward either side of the wearer will be obstructed for one eye by the shaded end wall of the device and that the depending point or projection 12 will perform the same function for the other eye. Also that when the wearer turns his eyes either to the right or left his field of vision will be limited for one eye by the shaded end wall nearest to it, and for the other eye by the provision 12. In other words the vision of the wearer to the sides is equalized so that he will not have his vision of a given object blocked for the near eye by an end wall of the device while the other eye is in position to see it, such partial vision resulting in confusion and annoyance to the wearer.

In some instances of use, as by the operator of a motion picture projector, it may be desirable to have the lower part of the device of relatively darker material so that the operator may clearly watch the screen through the upper part while his eyes are shaded from the light of the apparatus, usually below his lines of vision toward the screen.

While I have illustrated preferred and a slightly modified construction of the shield in its simpler properties, and preferred forms of certain coöperating features, the invention is not limited to what is specifically illustrated and described, as various changes may be made therefrom without departing from the spirit of this disclosure. Reference should therefore be had to the appended claims to determine the scope of the improvements herein set forth.

I claim:

1. In a two-piece eye protector proper, the combination of an upper portion of thin and flexible material through which the wearer may see and having light-obstructing properties adapted to shade the wearer's eyes, and a lower portion of thin and flexible substantially clear material

through which the wearer may see more clearly than through said upper portion secured to said upper portion along contiguous edge portions thereof intermediate the sides of the device, said upper and lower portions overlapping but slightly where so connected together. 70

2. A two-piece eye shield comprising an upper strip of thin and flexible material and a lower strip of thin and flexible material, 75 said lower strip having provisions to accommodate the nose of a wearer, said two strips being secured together at contiguous edge portions thereof intermediate the sides of the device, the end portions of said strips being formed and secured together to provide a wall at each end of the device, one of said strips extending substantially beyond the other at one end of the device and being folded upon said shorter end and secured thereto in overlapped relation to provide a smooth and continuous end wall on the outside of the device. 80

3. An eye protector comprising an upper strip of thin and flexible relatively dark 90 material and a lower strip of thin and flexible relatively clear material, said strips being connected together at contiguous edge portions thereof longitudinally intermediate the sides of the device, said lower strip having a recess to accommodate the nose of a wearer, end portions of said strips being turned inward and connected together to form a wall at each end of the device, and means for holding the device upon a wearer's face. 95

4. In an eye protector adapted to extend substantially across the face of the wearer, and having normally outwardly projecting concavo-convex portions at the ends thereof, the combination of a shade portion in the upper part of the device and a clear portion substantially in front of the wearer's eyes below said shade portion when the device is normally in use, said portions being joined together along contiguous edge portions thereof respectively intermediate the sides of the device, there being only one thickness of the material in the upper part of the device. 105 110

5. In an eye protector proper adapted to extend substantially across the face of the wearer, the combination of an upper portion of relatively dark thin and flexible material through which the wearer may see and adapted to shade an eye of the wearer and a lower portion of substantially clear thin and flexible material through which such shaded eye may view objects more clearly than through said upper portion when the device is normally in use, said upper portion and said lower portion being secured together at contiguous edge portions thereof intermediate the sides of the device, there being but one thickness of the material

in the upper portion of the protector proper, and means for securing the device upon the wearer's face.

6. In an eye protector of thin and flexible material adapted to extend substantially across the face of a wearer, the combination of upper and lower pieces of thin and flexible material secured together at contiguous edge portions thereof substantially longitudinally between the sides of the device, upper portions of the device being relatively dark to shade the eyes, lower portions thereof being substantially clear for seeing clearly therethrough, the device having provisions to accommodate the nose of the wearer, and means for securing the device upon the wearer's face.

7. In an eye protector, the combination of an upper shade part of thin and flexible material adapted to extend substantially across the face of the wearer, and a pair of substantially clear lower portions connected to said upper part at contiguous edge portions thereof intermediate the sides of the device, said clear portions having space provisions between them to accommodate the nose of the wearer, end portions of said upper and lower elements respectively being formed to provide a wall at each end of the device, and means for holding the device upon the wearer's face.

8. In an eye shield the combination of a front portion extending substantially from end to end of the device and having a ventilation opening therein, and an element positioned on what is normally the inner side of the device and adapted to deflect a current of air passing through said opening from the normally outer side of the device.

9. In an eye shield, the combination of a front portion of thin and flexible material extending substantially from end to end of the device, and having end walls, said front portion having a plurality of ventilation openings in what is normally the upper portion thereof, and means on what is normally the inside of said protector substantially overlying said openings adapted to deflect in a downward direction currents of air passing through said openings from the outside of said device when the device is normally in use.

10. An eye protector comprising in combination a body portion of thin and flexible

material extending substantially across the 55 face of the wearer when in use, and having a plurality of ventilation openings in the normally upper portion thereof, and a strip of thin and flexible material secured to the inside of said body portion above said openings, said strip substantially overlying said openings, the lower portion of said strip being spaced slightly from said body portion to deflect in a downward direction currents of air passing through said openings 60 from the front of the device when the same is normally in use.

11. In an eye shield of thin and flexible material adapted to extend across the face of the wearer and comprising a portion 70 through which the wearer may see clearly and a shade portion above said first mentioned portion when the device is normally in use, said shade portion extending substantially across the face of the wearer so 75 as to shade both eyes, a portion of said shade portion intermediate the ends of the device extending normally downward from said shade portion and substantially between the eyes of the wearer when the device is normally in use, said downwardly extending portion being adapted to protect an eye of the wearer from light rays passing slantingly substantially over the other eye.

12. A two-piece eye protector proper comprising an upper and a lower strip of thin and flexible material, said strips being connected together at contiguous edge portions thereof longitudinally intermediate the sides of the device, said lower strip having a recess intermediate the ends of the device to accommodate the nose of the wearer, end portions of said strips being turned inward and secured together to form a wall at each end of the device, said upper strip being 85 relatively dark to shade the wearer's eyes and having a portion thereof intermediate the ends of the device projecting in the direction of said nose recess and substantially 90 between the eyes of the wearer when the device is normally in use, said projecting portion constituting an intermediate shade 95 for the eyes.

FRANK HOWARD REXTREW.
